ATTACHMENT FOR SEWING MACHINES

Sarah M. Crewdson, Chicago, Ill., assignor of
one-third to Robert H. Goodhart, Chicago, Ill.

Application February 28, 1935, Serial No. 8,626

13 Claims. (Cl. 112—124)

The invention relates to an attachment for sewing machines and has for its object to provide an attachment that will trim a seam by cutting the material to form either a straight edge 5 or an irregular edge at a predetermined distance from the seam.

Another object of the invention is to provide an attachment of the character described that can be readily secured to a sewing machine in 10 a plurality of adjusted positions with respect to the needle to permit the operator to vary the distance of the severed edge from the stitching, thereby cutting margins of variable widths.

Another object resides in the provision of an 15 attachment that will embody novel means for operating the same from the reciprocating needle post of the sewing machine and which means will synchronize the cutting element with the feed mechanism of the machine so that the rate of 20 travel of the material through the machine will be the same as that through the attachment.

Another object of the invention is to provide 25 an attachment such as described which will accommodate thin material and also heavier thick material having resilient means for maintaining the proper pressure on the material during the cutting operation.

Another object of the invention is to provide 30 an attachment having a rotary cutting element for severing the material on a straight edge and which can be readily replaced by a rotary pinking element when it is desired to trim the edge with an irregular design.

The invention also contemplates the provision 35 of feed rollers for feeding the material through the attachment and novel mounting means for the lower feed rollers, whereby one of said rollers is resiliently held in engagement with the cutting element for performing the cutting operation and 40 which rollers may be locked against bodily movement in one direction to provide a solid and unyielding surface for the pinking element.

A further object is to provide a sewing machine 45 attachment of improved construction having rubber surfaced feeding rollers for positively feeding the material.

With these and various other objects in view 50 the invention may consist of certain novel features of construction and operation, as will be 55 more fully described and particularly pointed out in the specification, drawings and claims appended hereto.

In the drawings which illustrate an embodiment 55 of the invention and wherein like reference characters refer to like parts—

Figure 1 is a plan view of the attachment constructed in accordance with the invention and shown in association with the operating elements of a sewing machine;

Figure 2 is a side elevational view of the attachment of Figure 1 showing a pinking element 5 with feed rollers cooperating therewith;

Figure 3 is a side elevational view of the attachment of Figure 1, showing the operating mechanism for connecting the rotary cutting element with the sewing machine;

Figure 4 is a bottom plan view of the attachment;

Figure 5 is a sectional view taken substantially 15 along line 5—5 of Figure 4 showing a pinking element in contact with the feed roller and aprons for directing the material into engagement therewith;

Figure 6 is a detail sectional view taken along line 6—6 of Figure 2;

Figure 7 is a detail sectional view taken along line 7—7 of Figure 5; and

Figure 8 is a sectional view similar to Figure 7 but showing a rotary cutting element in association with the feed rollers.

The present invention particularly relates to 25 improvements over the form of mechanism for trimming seams shown in my copending application, Serial No. 743,642, filed September 12, 1934.

Referring to the drawings, the attachment has 30 been shown in associated relation with certain operating parts of a sewing machine of the type adapted for home use and which consists of a work supporting surface 10, a vertical reciprocating needle post 11 carrying a needle 12, and a supporting post 13 having the foot 14 secured thereto by the thumb screw 15 and which holds the material to be sewed in contact with feeding mechanism 16 of the sewing machine. It is to 35 be understood that the supporting post 13 can be vertically reciprocated by the operator and is yieldingly held in contact with the material during the sewing operation, being lifted by the operator to remove the same from the material 40 at the end of the sewing operation.

The attachment essentially consists of a frame member, Figure 1, which includes a vertical supporting member 18, having an inclined working surface 20 secured thereto. Extending from one 50 side of the member 18 is a boss 22 overlying but being spaced from the working surface as best shown in Figure 6. Extending from the member 18 below the working surface are two spaced bosses 23, Figure 7, and 24, Figure 6, which bosses 55

journal shafts to be presently described. The right angled strap members 25 and 26 are suitably bolted to the lower portion of wall 18 and to the surface 20, said strap members thereby supporting said surface from the member. Adjacent the base of said member and to the rear thereof is provided a laterally extending foot portion 27 which extends for part of the distance of the surface 20 to aid in supporting the frame in horizontal position on the surface 10 of the sewing machine.

The boss 22, Figure 6, journals a shaft 28 which projects from the end of the boss for receiving the washer 30, the cutting element 31 and retaining member 32, the parts being keyed and held fixed to said projecting end of the shaft by the bolt 33. The opposite end of shaft 28 projects from the wall 18 to which end is fixedly secured the ratchet wheel 34. Rotatably mounted on the end of shaft 28 projecting beyond the ratchet wheel is an operating arm 35 having the stud 36 integral therewith and which is held on the shaft by the bolt 37. The cutting element may take the form of a pinking knife for cutting an irregular edge or a cutting blade for severing the material along a straight edge.

One end of the operating arm, Figure 3, has the pawl 38 pivoted thereto as at 39 and which is held in contact with the ratchet wheel 34 by the coil spring 40. The other end of operating rod 35 is bent at right angles forming an intermediate section 41, shown in Figure 1, and which section is further bent and turned downwardly, forming the portion 42 having a recess for engaging the stud 43. Said stud has a knurled end 44 and is suitably secured to the reciprocating needle post 11 of the machine.

From the foregoing it will be understood that vertical movement of the needle post will oscillate arm 35 to cause engagement of pawl 38 with ratchet wheel 34, causing rotation of said ratchet wheel and shaft 28 in a counter-clockwise direction, Figure 3. Rotation of the shaft 28 by the reciprocating element of the sewing machine will therefore rotate the cutting blade of the attachment. A locking dog 45 is provided, pivoted to the wall at 46 and yieldingly held by spring 49 in contact with the ratchet wheel, in order to prevent reverse rotation of said ratchet wheel. However, the degree of oscillation of the arm 35 is in excess of that required to rotate the cutting element in synchronism with the feeding mechanism of the sewing machine, and accordingly the invention has provided means for disconnecting pawl 38 from the ratchet wheel at the end of the downward stroke of the arm. Said pawl carries at its extreme outer end the pin 47 and the wall 18 has suitably secured thereto an abutment 48 which is adapted to engage the pin to throw the pawl upward out of contact with the ratchet wheel. Thus the arm 35 has operative connection with ratchet wheel 34 for only a part of its downward stroke and by properly positioning abutment 48 the throw-off pawl 38 can be timed so as to accurately synchronize the speed of rotation of the cutting element with the feeding mechanism of the sewing machine so that just the amount of material supplied by the sewing machine is fed through the attachment. It will be understood that where it is possible to lengthen the arm 35 by locating the attachment further to the rear of the needle that the throw-off for the pawl can be dispensed with since under these conditions full engagement thereof for the downward stroke of the arm will be necessary to rotate

the cutting element at the proper speed. The invention also contemplates that the ratchet wheel 34 may be reduced in size and pivot 39 of pawl 38 relocated to secure the correct speed of the cutting element.

The work supporting surface 20 is provided with an opening directly below the cutting element 31, Figure 5. Part of this opening is closed by a rear apron 50 which is suitably secured as at 51 to the underside of surface 20. Forward of said opening there is provided a front apron 52 also suitably secured to the underside of surface 20, the free edge of said apron resting on the lower feed rollers 53 to direct the material between said cutting element and the feed rollers. Said feed rollers are journaled in a yoke 54 by means of the stud 55 passing through the arms of said yoke and which stud at its inner end is cut away on its lower side providing the flat surface 56, as shown in Figure 5. The yoke 54 is provided with a shaft 57 which is journaled in boss 23 of the vertical wall 18, the other end of said shaft extending beyond the boss and receiving the coil spring 58 which is retained thereon by the washer 59 and bolt 60. The coil spring therefore yieldingly holds the yoke in contact with the end of boss 23. The shaft 57 however mounts the yoke within the frame so that the same may have rotation, thereby supporting the feed rollers 53 for bodily movement in a direction toward and away from the cutting element. Movement of the feed rollers in this manner is desirable as it is necessary that the attachment accommodate thin, light material as well as heavy, thick material, and in order to apply the proper pressure on the material for feeding the same, a resilient member 61 is provided, said member having one end fixed to support 62 and its other end in engagement with the yoke 54.

By reason of the resilient member 61 the feed rollers will be yieldingly held in contact with the cutting element 31. However, for starting the material through the attachment it is desirable that the feed rollers be located out of engagement with the cutting element so that the material may be easily positioned therebetween. For accomplishing this a release lever 63 is provided, Figure 3, having the stud shaft 64 secured thereto, and which is mounted in the frame 18. Said stud shaft has fixed thereto on the opposite side of the frame the arm 65, Figure 5. Said arm overlies the projecting end of shaft 55 which journals the feed rollers so that actuation of lever 63 in a direction to impart clockwise rotation to arm 65 will rock the yoke 54 in a downward direction, moving the feed rollers out of contact with the cutting element. The cutting element 31 contacts the periphery of the inner feed roller and as the material passes between these two elements the same is severed, forming an irregular or pinked edge corresponding with the design of cutting element. For this operation it is necessary to lock the feed rollers against bodily movement as above described, since the severing of the material by element 31 would be impossible if the feed roller could be depressed. The locking means consists of an eccentric 66 carried by shaft 67 which is journaled in the boss 24 on the frame. On the opposite end of shaft 67 is suitably threaded a knob having a knurled portion 68 and a collar 70 which is flattened for a portion of its periphery and against which rests the strip of spring metal 71, Figure 3. The supporting stud 72 projects from the frame and positions said metal strip so that pressure

is maintained on the collar 70 of the wheel to prevent inadvertent rotation of eccentric 66. However, after the material has been located between the cutting element and the feed rollers 5 and it is desirable to lock the feed rollers against bodily movement, the operator grasps the knurled portion 68 and rotates shaft 67 and eccentric 66 until the same contacts with the flat surface 56 of the shaft 55. With the eccentric 10 in contact with the flat surface 56 of the shaft it is impossible to move the feed rollers in a direction downwardly and therefore said rollers provide a firm and unyielding surface for the cutting element.

15 In addition to trimming seams with an irregular design, which is accomplished by the pinking attachment 31, the present device is also capable of trimming said seams on a straight edge. The invention contemplates that the element 31 may be replaced by the upper feed rollers 53 and cutting blade 73. Figure 8 shows the association of the feed rollers with respect to the cutting blade, it being understood that the parts are keyed to the shaft 28 and retained 20 thereon by bolt 33 which likewise retains the element 31 thereon. The yoke 54 has been previously described as journaled in boss 23 in a manner permitting axial movement against the tension of the coil spring 58. This construction 25 has been provided in order to yieldingly hold one of the lower feed rollers 53 against the surface of the cutting blade 73, as shown in Figure 8. When the cutting blade is associated with the feed roller in this manner the parts effectively 30 perform a cutting operation, severing the material with a clean cut forming a straight edge. When the cutting blade has been substituted for the pinking element the locking eccentric 66 is rotated to position the same out 35 of contact with shaft 55 so that the yoke and the lower feed rollers have bodily movement, being yieldingly held in contact with the upper feed rollers located on the respective sides of the cutting blade. As shown in Figure 8, said upper 40 feed rollers are equipped with rubber tires 74. It is not absolutely necessary that the tires be composed of rubber as any friction material will function just as satisfactorily. The main object of surfacing the periphery of the upper feed 45 rollers in this manner is to insure positive feed of the material through the attachment.

The attachment is held in adjusted position on the surface 10 of the sewing machine by means of the scale 15 having graduations thereon and 50 being provided with an elongated slot 76. The member 18 is reduced in height at the end adjacent the supporting post 13 and is provided with a projecting screw 17 having the winged nut 18 thereon, the screw extending through the 55 slot in the scale, which is then held to the attachment by the winged nut. The scale 15 terminates in the upwardly bent portion 79, Figure 2, to which is pivotally secured a bent member 60 which may be considered as a separable part 65 of the scale. Member 80 is bent at one end to form a U-shaped portion which is adapted to overlie the secured portion of the foot 14 so that the foot and member are releasably secured to the supporting post 13 by the thumb screw 70 15. When the separable parts of the scale are rigid with each other vibrations from the sewing machine are readily transmitted to the attachment and in order to reduce these vibrations to a minimum the invention pivotally secures the 75 separable parts of the scale to each other by the

stud 81, which receives the coil spring 82 for yieldingly holding the parts together. By means of the pivotal relation between the parts of the scale the foot 14 can be raised by the operator a limited extent to adjust the material being sewed without detaching the part 15 of the scale from the attachment. This operation is necessary when it is desired to raise the foot 14 for its full height.

Figures 1 and 2 show a guard 83 for protecting the fingers of the operator from contact with the cutting element. Said guard is pivoted at 84 to a portion 85 secured to member 18. The pivot 84 is provided with resilient means to yieldingly maintain the guard in horizontal position with 15 the stop 86 in contact with the frame member as shown in Figure 6. This construction holds the guard in position for protecting the operator but can be easily lifted when it is desired to remove the cutting element from the attachment and 20 replace the same with a cutting element having other and different characteristics.

Projecting from frame 18 is a rod 87, as shown in Figure 1, to which is adjustably secured member 88, said member being adapted to be held 25 in position on said rod by tightening of the screw 90. The member forms a support for the material guide 91 to assist the operator in guiding the same from the needle of the sewing machine to the cutting mechanism of the attachment. 30 In the operation of cutting the material portions thereof find their way between the lower feed rollers 53. If the lint and scrap pieces of material are not removed from between the feed rollers they soon interfere with the operation 35 of the same. For this purpose the invention provides a stripping finger 92, Figure 2, suitably secured at one end to foot portion 27 having its free end located between the feed rollers 53. The finger is preferably of spring wire so that the 40 same maintains its position between the feed rollers, whereby the pieces of material and lint are effectively removed.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. An attachment for sewing machines comprising a rotary cutting element, means operatively connecting said element with a movable member of the sewing machine, whereby said element is rotated by the action of the machine, a scale adapted to be secured to a member of the machine and extending laterally with respect to the needle, means for adjustably securing the attachment to said scale, and means provided on the scale for absorbing the vibrations of the sewing machine whereby they are not transmitted to the attachment.

2. An attachment for sewing machines comprising a rotary cutting element, means operatively connecting said element with a movable member of the sewing machine whereby said element is rotated by the action of the machine, a scale adapted to be secured to a member of the machine and extending laterally with respect to the needle, and means for adjustably securing the attachment to said scale, said scale comprising two sections pivotally secured together whereby the vibrations of the sewing machine are not transmitted to the attachment.

3. An attachment for sewing machines comprising a rotary cutting element, means operatively connecting said element with a movable member of the sewing machine whereby said element is rotated by the action of the machine, a scale adapted to be secured to a member of the machine and extending laterally with respect to the needle, and means for adjustably securing the other end of the scale to said attachment, 10 said scale having a yielding joint intermediate its ends for absorbing the vibrations of the sewing machine whereby they are not transmitted to the attachment.
4. An attachment for sewing machines, comprising a frame member having a rotary cutting element, a feed roller positioned below the cutting element, means journaling said roller and being mounted in the frame for movement in a direction parallel to the axis of the roller, and means 20 biasing the mounting means in a direction to hold the feed roller in engagement with the cutting element for performing a cutting operation.
5. An attachment for sewing machines, comprising a frame member, a shaft mounted for rotation in said member and carrying a cutting blade, a feed roller positioned below said blade and having association therewith to perform a cutting operation, means journaling said roller, 30 said means being mounted for movement in the frame in a direction parallel to the axis of the roller, and resilient means biasing said mounting means to maintain the cutting blade and roller in contact.
- 35 6. An attachment for sewing machines, comprising a frame member having a rotary cutting element, a feed roller positioned below the cutting element and having contact therewith for performing a cutting operation, means journaling the feed roller, a shaft carrying said means and being mounted in the frame for movement in a direction parallel to the axis of the roller, and resilient means on the shaft for biasing the journaling means in a direction to hold the feed 45 roller in contact with the cutting element.
7. An attachment for sewing machines, comprising a frame member having a rotary cutting element, a roller positioned for contact with the cutting element, means journaling said roller, a shaft carrying said journaling means and being mounted in the frame for rotation, resilient means forcing the roller into contact with the cutting element, and a manually operable lever for holding the roller out of contact therewith.
- 50 8. An attachment for sewing machines, comprising a frame member having a rotary cutting element, a roller positioned for contact with the cutting element, means journaling said roller, a shaft carrying said journaling means and being mounted in the frame for rotation, whereby said roller is supported for bodily movement, resilient means biasing said shaft to force the roller into 55 contact with the cutting element, and a manually operable lever adapted to engage the journaling means to depress the same against the tension of the resilient means.
9. An attachment for sewing machines, comprising a frame member having a rotary cutting element, a roller positioned below the cutting element, a yoke journaling the roller and being rotatably mounted in the frame, whereby said roller is supported for bodily movement, resilient means forcing the yoke upward to hold the roller in contact with the cutting element, and a lever adapted to be manually actuated for holding the roller out of contact with the cutting element. 60
10. An attachment for sewing machines, comprising a frame member having a rotary cutting element, a roller positioned below the cutting element, a yoke journaling the roller and being rotatably mounted in the frame, whereby said roller is supported for bodily movement, resilient means yieldingly holding the roller in contact with the cutting element, and a manually operable lock for locking the yoke preventing downward movement of the same. 65
11. An attachment for sewing machines, comprising a frame, a shaft journalled in the frame and carrying a cutting blade, feed rollers fixed to the shaft and positioned on the respective sides of the blade, lower feed rollers located below the blade, a yoke journaling the lower feed rollers and being rotatably mounted in the frame, whereby said rollers are supported for bodily movement, and resilient means biasing the yoke to yieldingly hold the lower feed rollers in contact with said first mentioned feed rollers. 70
12. An attachment for sewing machines, comprising a frame, a shaft journalled in the frame and carrying a cutting blade, feed rollers fixed to the shaft and positioned on the respective sides of the blade, means rotating said shaft whereby said feed rollers are driven, lower feed rollers located below the blade, a yoke journaling the lower feed rollers and being rotatably mounted in the frame, resilient means yieldingly forcing the yoke upward to hold the lower feed rollers in contact with the driven rollers, and a lever adapted to be manually actuated for holding the lower rollers out of contact with said driven rollers. 75
13. An attachment for sewing machines comprising, a rotary cutting element, a rotatable shaft therefor, means operatively connecting said cutting element with a reciprocating member of the machine whereby said element is rotated by the action of the machine, said means including a ratchet wheel fixed to said shaft, an arm pivoting on the shaft and carrying a pawl engaging the ratchet wheel, and an abutment for disconnecting the pawl for a part of the downward oscillating stroke of the arm. 80

SARAH M. CREWDSON.
